CHILD'S HIGH CHAIR

Dale Merchant, Elkhart, Ind.

Application March 16, 1936, Serial No. 69,029

3 Claims. (Cl. 155—189)

My invention relates to improvements in child's high chair and it more especially consists of the features pointed out in the claims.

The purpose of my invention is to provide a high chair for young children that will effectively prevent the child rising from the seat, standing on it and running the risk of falling off onto the floor and receiving serious injuries; that provides means on the seat of the chair to hold the legs spaced apart and also provides means above the legs which will prevent the child lifting its legs. It is a well known fact that so long as the legs cannot be straightened at the knee it is impossible for the child to stand erect. My safety provision eliminates the usual straps for allegedly tying the child onto the chair and the use of a canvas with leg openings dropping down from the swinging tray support. My invention is specially directed to the use of means that will positively hold the legs spaced apart on the seat of the chair.

With these and other ends in view I illustrate in the accompanying drawing such instances of adaptation as will disclose the broad features of the invention without limiting myself to the specific details shown thereon and described herein.

Fig. 1 is a front elevation partly in section.

Fig. 2 is a side elevation partly in section.

Fig. 3 is a top plan view of the seat of the chair.

Fig. 4 is a fragmentary sectional elevation of a tray catch.

Fig. 5 is a fragmentary sectional elevation of a tray support catch.

In the use of a child's high chair made according to my invention I may employ whatever alternatives or equivalents of structure that the exigencies of varying conditions may demand without departing from the broad spirit of the invention.

I may use any desired form of high chair provided with a seat 1, a back 5, a foot rest 7, supporting legs 6, side arms 9 and a swinging or adjustable tray support 8 and combined with it a pair of openings 2 in the seat of the chair, the rear edges of which are beveled off at 4 and rounded at 3 and also rounded at 3 along the sides and front of the openings to provide comfort for the child.

I may use any desired form of automatic catches for locking the tray support 8 to the side arms 9 as shown in Fig. 5 or I may use a strap 15 with buckle or other fastening for securing the tray support 8 to the seat 1 as shown in Fig. 1.

The stock member 12 for preventing the child raising its legs preparatory to standing up is provided with curved recesses 13. The margins 14

of the recesses 13 nearly touch the seat of the chair so that there is no possibility of the child wiggling its legs sideways and freeing them from restraint. The member 12 is secured to the underside of the tray support 8 by brackets 18 which are adjustable on the underside of the tray into different positions forward and backward where it is held by wing nuts 20. If made non-adjustable, the wing nuts 20 would be replaced by ordinary screws. The foot rest 7 is adjustable vertically on the front legs 6 by means of pins 21 entering holes 22.

The tray support 8 shown in Fig. 4 may have a removable tray 10 supported thereon and held in place by spring clips 11. This permits the easy removal of the tray for washing, etc. The tray 10 has a depressed portion 24 and a rim 25 which rests on the margins of the tray support 8. The spring clips 11 shown in dotted lines in Fig. 4 terminate in hooked ends 26. These ends simply depend into the recess portion of the tray.

Many serious accidents have occurred in the use of ordinary high chairs due to a child standing up and falling to the floor, sustaining injuries that may form a handicap throughout life because the grown person will be crippled as a result of an accident in childhood which through the present invention is fortunately preventable.

The forward or backward adjustment of the stock member 12 on the underside of the tray support 8 has been described above. In order to automatically hold the tray support 8 in position on the side arms 9 after its curved supports 17 have been swung forward on pivot 16, a spring catch 19 automatically enters an opening 23 formed in the inner face of a side arm 9 as shown in Fig. 5.

What I claim is:—

1. A child's high chair comprising a seat having spaced apart openings therein in close proximity to its front edge, a back, arm rests, a tray supported on the arm rests, a guard member adjustably mounted on the underside of the tray, spaced openings extending from the lower edge of the guard said openings being approximately in line with and directly over the seat openings, and a foot rest on the chair legs approximately in line with the front edge of the seat openings.

2. A child's high chair comprising a seat having spaced apart openings therein in close proximity to its front edge, a back projecting upward from the rear edge of the seat, arm rests attached to the back and projecting forward therefrom, supports for the front end of the arm rests placed between the arm rests and the seat, a

removable tray support on the arm rests, a guard member on the under side of the tray support, spaced openings extending from the lower edge of the guard said openings being approximately in line with and directly over the seat openings, chair legs depending from the seat, a foot rest on the chair legs approximately in line with the front edge of the seat openings, and means for attachably and detachably holding the tray support on the arm rests.

3. A child's high chair comprising a seat having a pair of spaced apart openings therein, a back projecting upward from the rear of the

seat, raised arm rests along each side of the seat, legs depending from the seat, a foot rest supported on the legs approximately in line with the front edge of the seat openings, means for holding a tray support on the arm rests in spaced apart relation to the back, a leg retaining member having curved recesses corresponding to the spacing of the seat openings, and means for adjusting the retaining member toward and forward from the back whereby the recesses may be positioned directly above the openings of the seat.

DALE MERCHANT.
